UNITED STATES PATENT OFFICE.

JOHN J. FRANK, OF SCHENECTADY, NEW YORK, ASSIGNOR TO GENERAL ELECTRIC COMPANY, A CORPORATION OF NEW YORK.

TRANSFORMER.

No. 885,034.

Specification of Letters Patent.

Patented April 21, 1908.

Application filed September 26, 1907. Serial No. 394,658.

To all whom it may concern:

Be it known that I, JOHN J. FRANK, a citizen of the United States, residing at Schenectady, county of Schenectady, State of New

5 York, have invented certain new and useful Improvements in Transformers, of which the following is a specification.

My invention relates to transformers which are especially intended for very high voltages, and has for its object an improvement 10 in the insulation between the coils or the coils and the low-potential portions, such as the core or the inclosing casing, so that the high voltage stresses to which the insulation 15 is subjected may be better withstood, and thus short-circuits between the high voltage and the lower voltage portions may be prevented.

In the construction of electrical apparatus, 20 and especially transformers, where only a small portion of the conductors is subjected to a very high voltage, it is found extremely difficult to provide such insulation for the conductors that a high voltage may be maintained without a break-down of the insulation. If, however, the high potential stresses set up in that portion of the insulation adjacent to the high voltage portion of the conductors can be distributed over a large area 25 of the insulation surrounding the conductors, the amount of stress to which any portion of such insulation will be then subjected will be less, for the intensity of the stress will be decreased as it is extended over a 30 large area. The insulation about such high voltage conductors will then be less liable to be "broken down" than if a smaller portion of the insulation be subjected to a greater stress.

40 The object of my invention is to decrease and distribute this high potential stress which normally occurs over a small portion of the insulation over a greater portion of such insulation, and thus afford a better protection 45 against short circuits in the transformer. I accomplish this by surrounding the coils of high voltage conductors, which may already have their several turns insulated from adjacent turns, with parallel layers of a conducting material interspersed with layers of an insulating material; the several layers of conducting material being insulated from each other. The conducting material then

serves to form high potential surfaces and thus distribute the high potential stresses 55 over a large area of the insulating material.

In order to decrease the potential stresses through the insulation, I make the several parallel layers or sheets of conducting and insulating material greater in area as they 60 are spaced a greater distance from the high voltage conductors. By so doing the first sheet of conducting material becomes subject to a certain potential per unit area, the next sheet is subject to a certain potential, 65 but being a greater area than the first sheet, and distant from the first sheet, the potential per unit area is much less than that of the first sheet. By employing a number of these sheets the resulting potential stress per 70 unit area of the insulation between the sheets, the conducting material and the final sheet may be made comparatively small, and thus the insulation between the final sheet and the conducting material adjacent to it may either 75 be made small in quantity or a greater amount of a poorer quality of insulation may be employed.

While I may accomplish the object of my invention in many ways, I prefer to accomplish it by the use of sheets consisting of a sheet of an insulating material, such for example as varnished cambric, to which is attached by a suitable adhesive substance, such as shellac, a thin sheet of some metallic 85 substance, for example tin foil. These sheets may consist of one layer of cambric and one layer of tin foil, or, if desired, of a number of alternate layers of varnished cambric and tin foil to still better equalize the potential 90 stresses through the insulation. The shellac holding the tin foil to the varnished cambric may be omitted but I prefer to use it or some other adhesive substance for convenience in manipulation. The compound insulating sheet thus constructed may then be readily formed into any of the desired shapes required for insulating purposes, and, if desired, any number of these sheets may be used to further increase the insulation. 100

In the accompanying drawings attached to and made a part of this specification, Figure 1 shows a vertical view of a transformer with my improved insulation; the surrounding case and one of the coils, with portions of the insulation shown in section to obtain a better 105

understanding of my invention; Fig. 2 shows a top view of the same transformer, with the top and terminal bushings removed, and Fig. 3 shows a portion of my improved insulation.

- 5 While I may employ my new method of insulation with any type of transformer, I have shown it employed with an oil insulated core-type transformer, in which 1 represents the base of the transformer to which may be attached by any suitable means a shell or casing 2, to which is attached the top 3; the joints between 1 and 2 and 2 and 3 being formed in any well-known manner, so that they be oil-tight. The cover 3 has formed in it holes 4 and 4' to allow suitable terminals to be brought out from the transformer coils and other holes, such as 4",—which may be useful and necessary for inspecting the inside of the transformer, or putting in oil etc.
- 10 5 shows the core of the transformer, which may be formed of bundles of laminæ in the well known fashion; the bundles being held together by bolts 6, passing through suitable cross-pieces 7 and fastened by nuts 8.
- 15 25 As that portion of the structure of the transformer that relates to the retaining of the core and the coils, and the holding of the same together and to the casing is immaterial to my present invention, I shall not further describe it; but shall confine my description to those portions of the transformer to which my invention relates.

9 is the primary or low-voltage winding closely fitting the core, and 10 the secondary or high-voltage winding; this being shown as divided into short coils, for convenience in insulating the coils. These short coils are separated from each other by strips of an insulating material 11, which are shown as not 20 extending over the entire faces of the coils, but allowing spaces 12 to permit of a flow of cooling fluid between the coils. I have shown the upper coils as somewhat thicker than the lower as the insulation between the turns 25 may be increased in the well-known manner to further provide against a short circuit between the several turns subjected to the high potential between the coils.

13 are blocks of wood, which serve as supports for the coils; the inside of the coil being lined by a strip of insulating material, 14, fiber, or any other suitable substance.

Terminals 15 are shown leading from the primary winding through suitable insulating bushings 16 to the exterior of the casing of the transformer, and terminals 17 leading from the secondary windings through suitable high-tension bushings 18 to the exterior of the transformer.

60 Sheets of my improved insulation 19 are shown between the primary and secondary coils; these sheets being separated by suitable insulating space-blocks to make spaces 20 between the insulating sheets and the

primary and secondary winding, through 65 which spaces of insulating fluid may be allowed to flow. Insulating sheets 21 are also shown between the coils of the transformer, the sheets being supported by insulating blocks 22 to provide spaces between the 70 sheets and the coils for the purpose previously described. All of these sheets are shown extending well beyond the ends of the coils and successively greater in area as they are spaced further from the high voltage 75 conductors, and sheets 21 are shown as extending in a horizontal direction well beyond the exterior faces of the coils, to give a greater voltage creepage distance. I have also shown sheets of insulation 23 extending around the 80 interior of the casing of the transformer and resting upon and separated by insulating blocks 24 and space-blocks 25. These sheets 23 I have shown as extending to the top of the casing, for while the terminals 17 are 85 shown as insulated by the high-voltage bushings 18, it has been found that frequently a short-circuit will occur between the terminals 17 and the casing, and by extending my improved insulation about the casing, well 90 above the terminals 17, and making the sheets greater in area as they approach the casing, I distribute and diminish the potential stress due to the terminals over a wide area of insulation for the reasons previously 95 described.

In Fig. 3, I have shown a portion of my insulation consisting of a layer of insulating material 26 attached to a thin conducting sheet 27; a cover of the sheet 27 being rolled away from the insulating material. While I have shown my insulation as consisting of one layer of conducting and one layer of insulating material, for greater clearness in illustration, I do not limit myself to a single 100 sheet in each, but a number of sheets alternately of a conducting and an insulating material may be used if desired, and these may or may not be fastened together by an adhesive substance, such as shellac, for example.

While I have shown my invention as applied to a certain type of apparatus, namely, an oil-insulated core-type of transformer, it should be understood that my invention is not limited to such an apparatus, but may be used with any type of electrical apparatus where certain portions are subjected to a high voltage, substantially for the purpose and in the manner described.

What I claim as new and desire to secure by Letters Patent of the United States, is,—

1. In an electric device containing conductors subject to a high voltage and adjacent to other conductors or conducting material, means for insulating the high-voltage conductors by interposing between them and the low-voltage conductor or the low-voltage

conducting material adjacent to them parallel layers of an insulating and an insulated conducting substance.

2. In an electric device containing conductors subject to a high voltage and adjacent to other conductors or conducting material, means for insulating them from the low-voltage conductors or conducting material by surrounding them with insulated layers of conducting material, the layers being successively greater in area as they are successively spaced further from the high-voltage conductors to decrease and equalize the high potential stresses over a large area of the insulation.

3. The combination with an electric device containing conductors subject to a high voltage and adjacent to other conductors or conducting material of an insulation surrounding the high-voltage conductors composed of a plurality of parallel sheets composed of layers of an insulating material and an insulated conducting material, the sheets being successively greater in area as they are successively spaced further from the high-voltage conductors and spaces between the sheets containing insulating fluid.

4. In a transformer composed of a primary and a secondary winding, means for decreasing and equalizing the potential stresses due to one of the windings over a large area of the insulation between the windings.

5. In a transformer composed of a primary and a secondary winding, one winding having high potential in certain portions, a laminated core and an inclosing casing, means for decreasing and equalizing the potential stresses due to a portion of one of the windings over a large area of the insulation between said winding, the core and the casing.

6. In a transformer composed of a primary and a secondary winding with a laminated core and an inclosing casing, and high-potential terminals adjacent to the sides of the casing, means for decreasing and equalizing the potential stresses due to said terminals over a large area of the insulation of said casing.

7. In a transformer composed of a primary and a secondary winding, one of the windings having high potential in certain portions, an insulation composed of a plurality of parallel layers of an insulated conducting substance, and an insulating substance for decreasing the potential stresses due to one of said windings and equalizing them over a large portion of the insulation between said windings.

8. In a transformer composed of a primary and a secondary winding with a laminated core and an inclosing casing, an insulation composed of a plurality of parallel layers of an insulated conducting substance, and an insulating substance for decreasing the potential stresses due to one of said windings and equalizing them over a large area of the

insulation between said winding, the core and the casing.

9. In a transformer composed of a primary and a secondary winding, one of the windings having high potential in certain portions, an insulation composed of a plurality of parallel layers of an insulated conducting substance, and an insulating substance, the layers being successively greater in area as they are successively spaced further from the high-voltage winding, for decreasing the potential stresses due to one of said windings and equalizing the stresses over a large portion of the insulation between said windings.

10. In a transformer composed of a primary and a secondary winding with a laminated core and an inclosing casing, an insulation composed of a plurality of parallel layers of an insulating conducted substance and an insulating substance, the layers being successively greater in area as they are successively spaced further from the high-voltage conductors for decreasing the potential stresses due to one of said windings and equalizing the stresses over a large area of the insulation between the said winding, the core and the casing.

11. In a transformer composed of a primary and a secondary winding with a laminated core and an inclosing casing, and high-potential terminals adjacent to the sides of the casing, an insulation composed of a plurality of parallel layers of an insulated conducting substance and an insulating substance for decreasing the stresses due to the potential of said terminals and equalizing the stresses over a large area of the insulation adjacent to the casing.

12. In a transformer composed of a primary and a secondary winding with a laminated core and an inclosing casing and high-potential terminals adjacent to the sides of the casing, an insulation composed of a plurality of parallel layers of an insulated conducting substance and an insulating substance, the layers being successively greater in area as they are successively spaced further from the high-potential terminals for decreasing the stresses due to the potential of said terminals and equalizing the stresses over a large area of the insulation adjacent to the casing.

13. The combination with a transformer consisting of a primary and a secondary winding, of an insulating material inclosing said coils consisting of parallel layers of an insulating and a conducting substance.

14. The combination with a transformer consisting of a primary and a secondary winding, a core and an inclosing casing, of an insulation composed of a plurality of parallel layers of an insulating and a conducting material, the layers being successively greater in area as they are successively spaced further from the high-voltage conductors, and spaces

between said layers filled with an insulating fluid for increasing the insulation.

15. In a core-type transformer consisting of a core, primary and secondary windings inclosing the legs of said core substantially as shown, one of said windings having a maximum potential at portions of said winding, an insulating material composed of a plurality of parallel layers of an insulated conducting substance and an insulating substance concentric to said coils and between said coils, the layers being successively greater in area as they are successively spaced further from the high-voltage conductors to decrease the potential stresses between said coils and equalize the stresses over a wide area of the insulation separating said coils.

16. In a core-type transformer consisting of a core, primary and secondary windings inclosing the legs of said core substantially as shown, one of said windings having a maximum potential at certain portions, and an inclosing casing, an insulating material composed of a plurality of parallel layers of an insulated conducting substance and an insulating substance, the layers being successively greater in area as they are successively spaced further from the high-voltage conductors to decrease the potential stresses due to the high potential of one of said windings and equalize the stresses over a large area of the insulation between said winding, the core and the casing.

17. In a core-type transformer consisting of a core, primary and secondary windings

inclosing the legs of said core substantially as shown, and high-potential terminals adjacent to said casing, an insulating material consisting of a plurality of parallel layers of an insulated conducting substance and an insulating substance, the layers surrounding the inner side of said casing and being successively greater in area as they are successively spaced further from the high voltage conductors, for decreasing the potential stresses due to said terminals and equalizing the stresses over a wide area of the insulation adjacent the casing.

18. In combination with an oil insulated core-type transformer with a core, primary and secondary windings upon the legs of said core, an inclosing casing, high-voltage terminals brought out adjacent to the sides of said core of an insulation composed of a plurality of layers of an insulating and an insulated conducting substance between the windings, the core and the windings, and surrounding the inner side of the casing of the transformer, the layers being successively greater in area as they are successively spaced further from the high-voltage conductors, substantially as shown and for the purposes described.

In witness whereof, I have hereunto set my hand this 24th day of September, 1907.

JOHN J. FRANK.
